UNITED STATES PATENT OFFICE.

MAX HADAM, OF CHEMNITZ, GERMANY, ASSIGNOR TO MASCHINENFABRIK KAPPEL, A.-G., OF CHEMNITZ-KAPPEL, GERMANY.

JACQUARD MECHANISM FOR EMBROIDERING MACHINES.

Application filed May 15, 1925, Serial No. 30,580, and in Germany July 9, 1924.

This invention relates to jacquard operated mechanism for braiding, net or lace making machines and the like, of the kind shown in U. S. Patent 1,005,436 granted to Johann 5 Jacob Knecht, October 10, 1911 wherein the various motions of the needles as controlled by the jacquard mechanism are transmitted to planet wheel carriers which co-act with planet gear to cause axial displacements of 10 endless screws, such displacements controlling the position of the embroidery frame. In such machines the planet wheel carriers are at present caused to oscillate through their required angles by means of complicated toothed mechanism, which is expensive to produce, and which, when worn, causes irregularities in the extent of the oscillation of each separate planet wheel carrier.

20 The object of the present invention is to avoid these objections, and this is effected by transmitting the motions of the needles as determined by the jacquard mechanism to the planet wheel carriers by means of lever 25 pawls, and employing a stop-lever to hold each carrier in its exact position. The transmission of motion from the planet wheel carriers to the embroidery frame is performed as at present.

30 The invention is illustrated diagrammatically by way of example in the accompanying drawings, in which for the sake of clearness, only one drive for a planet wheel carrier as effected by the jacquard mechanism is 35 shown. In the drawings,

Figure 1 is a side view thereof.

Figure 2 is a front view of a series of planet wheel carriers and of the accompanying pawl levers which effect their oscillations. The planet gear for the planet wheel carriers is not shown in detail since it is known and furthermore the present invention is not concerned therewith.

In carrying the invention into effect, the 45 known series of differential drives constituted by the planet gears such as shown in U. S. Patent No. 1,005,436, referred to above are mounted on a shaft 3, which is supported in the side frames 1-2 of the machine. 50 The planet wheel carriers 4 are in the form of discs, of which seven are shown in Figure 2, arranged side by side on the shaft 3. The discs 4 are mounted loosely on the shaft 3 as in known practice but co-act with planet 55 gear as before described to transmit motion

to the embroidery frame. They receive their partial rotation selectively according to the pattern of the jacquard card. They have mounted on them engaging members in the form of pins or rollers 5, spaced apart at 60 equal distances. Beneath the differential shaft 3 and parallel therewith is mounted a shaft 6, on which are loosely pivoted the levers 7. These levers are arranged one pair at each side of the machine and the respective pairs are connected by spindles 8 and 9, on which there are also loosely mounted the pawl levers 11 and 10 on opposite sides of the axis of oscillation 3 of the planet wheel carriers 4. By means of a cam 12, 70 shown in Figure 1, a slide 13 is caused to rise and fall in guides, and this slide is connected by rods 14 and 15 to the spindles 8 and 9 respectively, the latter being thereby caused to rise and fall, pivoting about the 75 axis 6. The extreme end positions of the spindles 8 and 9 are indicated in Figure 1, in full and dotted lines. The distance between their extreme positions exactly corresponds to the distance apart of the pins or rollers 80 5 on the planet wheel carrier discs 4. At a point to one side of the mechanism described, and above the level of the shaft 3, there is supported a spindle 16, on which stop-levers 85 17 are loosely pivoted, one such lever being provided for each of the discs 4. Each stop-lever 17 has a groove at its free end adapted in the swinging of the lever to embrace one of the pins 5 of the planet wheel carrier, when the oscillating movement of 90 the said carrier has been completed by the selected pawl lever 10 or 11, as hereafter described.

The pawl levers 11 have each a nose piece 95 35 at their upper ends, which are adapted to engage the inclined grooves 17^a on the lower side of the stop-levers 17 and raise them out of operative position prior to the commencement of the oscillating movement of the planet wheel carriers 4.

100 The direction of oscillation of any given planet wheel carrier disc is determined by the jacquard card mechanism, which is illustrated diagrammatically at the left hand side of Figure 1. This mechanism selects 105 the pawl lever 11 or the pawl lever 10 as the effective operating member for the oscillation of the carrier, and thereby determines whether the said carrier will oscillate in a clockwise or a counter-clockwise direction. 110

The jacquard card 18 is fed over the bar 19, which is moved backwards and forwards in the known manner at each advance of the card from the dotted position shown to the full position shown in Figure 1. In this way, when the needle 20 comes opposite a perforation in the jacquard card, the said needle is undisturbed, but if no perforation is on the card, the needle 20 is moved to the right looking at Figure 1. The needles 20 are attached to jacks 21 and 22, which have butts 23 and 24 adapted to co-operate or not, according to the position of the perforations on the jacquard card 18 with the feeler levers 28 and 29.

Loosely mounted on a spindle 25 there is a lever 26, which is adapted to be oscillated in step with the rising and falling of the slide 13, by means of a connecting rod 30. The connecting rod 30 has an elongated slot 30^a at its end, and the pin 26^a on the lever 26, which engages in this slot, is held against the lower end thereof, by means of a spring 38. The lever 26 carries a cross-spindle 39, on which the three-armed lever 27 is mounted. On the horizontal arms 27^a—27^b of this lever are pivoted the feeler levers 28 and 29, which co-operate with the butts 23, 24 of the jacks 21, 22 as above mentioned, and to the vertical arm there is connected a link 33, which operates the end of the pawl levers 11 and 10, which are held apart, one on each side of the centre of oscillation 3 of the planet wheel carrier 4 at the required distance, by means of a tie link 34. The link 34 is of such length that both pawl levers 10 and 11 may be out of engagement at the same time. The three-armed lever 27, by its articulation to the pair of pawl levers, is adapted to move these levers in unison transversely to the axis of rotation of the planet wheel carriers, and thereby to bring one or other of the pawl levers 10 or 11 into operative position.

Connected with the mechanism described there is a machine stop gear provided, which may be of any convenient form, and is set in operation by the mechanism here described. In the form shown, the actuating mechanism is illustrated as a Bowden wire mechanism, and comprises a central core wire 37, which passes through the outer cable 36, which is fixed to some point on the rod 30. The core wire 37 is fixed to some suitable point of the lever 26, near to its free end.

The method of operation of the mechanism is as follows:—

The jacquard cylinder 19 on its approach 60 presses for example the needle 20, connected to the jack 22, from left to right, looking at Figure 1, whereby the butt 24 is moved out of alignment with the feeler lever 29. If the jack 21 had been selected, the butt 24 65 would have remained in alignment with the

feeler 29, and the butt 23 would have moved out of alignment with the feeler lever 28. The movement of the jacks is thus in accordance with the pattern of the jacquard card and synchronizes with the downward movement of the cross-spindle 39, under the action of the lever 26. In this way the three-armed lever 27 is tilted in a clockwise or counter-clockwise direction, when the lever 26 is moved downwardly. At the same time, the slide 13 is at the upper end of its travel, and in the position illustrated in Figure 1, the three-armed lever 27 has been tilted to move the pawl lever 11 into engagement with one of the pins 5 on the disc 4 shown, whilst the pawl lever 10 is left free. During this engaging movement of the lever 11, the nose 35 slides along the inclined groove 17^a on the underside of lever 17, thereby raising the said lever out of engagement with the pin or roller 5, which it was embracing. The disc 4 is then free to rotate.

When the slide 13 moves downwards, the disc 4 is rotated through an angle corresponding to the distance apart of the pins or rollers 5. At the same time the connecting rod 30 has moved the lever 26 upwards, so that the arms 27^a—27^b of the three-armed lever 27 impinge against the fixed rails 31—32 and the lever is thereby tilted in a counter-clockwise direction from the position illustrated in Figure 1. In this way the pawl lever 11, when in the dotted position illustrated in Figure 1, is withdrawn from engagement with the pin or roller 5, and the stop-lever 17 then engages over the next pin on the disc. The disc has thus been given a counter-clockwise movement through an angle of 60 degrees in the form illustrated. It will be readily understood in the event of the butt 24 coming into operation, the rotation of the disc would be through an angle of 60 degrees in a clockwise direction.

If the jacquard card should be torn, or should any mistake have been made in perforating the card, both jacks 21 and 22 will remain undisturbed, and both butts 23 and 24 will register with the feeler rods 28 and 29. In this case the lever 26 will be arrested before it completes its downward movement, and the continued downward movement of the connecting rod 30 will cause the spring 38 to stretch, and the core 37 of the Bowden mechanism will be pulled through the cable 36, whereby the machine is stopped in any convenient manner.

I claim:

1. In a lace machine wherein the motions of needles actuated by jacquard card mechanism are transmitted to planet wheel carriers co-acting with planet gear to actuate the embroidery frame, means for operating each planet wheel carrier, comprising a pair of pawl levers, members on the planet wheel 125

carrier adapted to be engaged by one or other of the said pawl levers, means for moving one or other of said pawl levers into engaging position, a stop-lever and 5 means for disengaging the stop-lever from the planet wheel carrier when the selected pawl lever is brought into engagement with one of the engaging members of the planet wheel carrier.

10 2. In a lace machine planet wheel carrier, (as in claim 1) comprising two lever pawls, located one on each side of the centre of oscillation of the planet wheel carrier, pins on the planet wheel carrier with which one 15 or other of said pawl levers engages to oscillate the planet wheel carrier in one or other direction, jacquard actuated means for selecting which of the pawl levers is in engaging position, a stop-lever adapted to engage one of the pins on the planet wheel 20 carrier, and means on the pawl levers for disengaging the said stop-lever as one or other of the pawl levers is placed in engaging position.

25 3. In a lace machine planet wheel carrier (as in claim 1) comprising two pawl levers located one on each side of the axis of oscillation of the carrier, a link connecting said pawl levers and holding them at a 30 predetermined distance apart, means for raising and lowering said pawl levers together, pins on the planet wheel carriers spaced apart at equal distances and with which said pawl levers are adapted to engage, a three-armed lever articulated to said pawls to move them in unison transversely to the axis of oscillation of the carriers to engage one or other of said pawl levers with the pins on the carrier, feeler bars on the 35 said three-armed lever, jacquard-operated jacks co-operating with said feeler bars, an oscillating lever carrying said three-armed lever and moving said feeler bars into engagement with said jacquard operated jacks, and a stop-lever for arresting the 40 carrier in the position to which it has been moved by the pawl lever.

45 4. In a lace machine wherein the motions of needles actuated by jacquard card mechanism are transmitted to planet wheel carriers co-acting with planet gear to actuate an embroidery frame, the combination of side frames, a transverse shaft supported in said frames, planet wheel carriers grouped on said shaft, two pawl levers for each planet wheel carrier arranged one on each side of said shaft, a second transverse shaft, levers mounted on said second shaft at each end thereof, cross bars connecting

said levers and on which said pawl levers 60 are mounted, means for oscillating the levers on said second shaft, a rod connecting said pawl levers to hold them apart at a predetermined distance and jacquard-operated means for oscillating said pawls in 65 unison transversely to the axis of rotation of the planet wheel carriers to select which of said pawl levers shall operate the said carrier, substantially as described.

5. In a lace machine wherein the motions 70 of needles actuated by jacquard card mechanism are transmitted to planet wheel carriers co-acting with planet gear to actuate an embroidery frame, jacquard operated mechanism for selectively oscillating the 75 planet wheel carriers in one or other direction, comprising two sets of slidable jacks having differently-located butts thereon, a jacquard card mechanism operating said jacks selectively, a three-armed lever, an oscillating lever carrying said three-armed 80 lever, feeler bars on two arms of said lever adapted on the oscillation of the carrying lever to co-operate with the butts on said jacks which have not been operated by the 85 jacquard mechanism, an actuating rod for said carrying lever, said actuating rod having an elongated slot therein, a pin on the free end of the carrying lever engaging in the elongated slot, a spring holding said 90 pin at one end of said slot, a Bowden core wire fixed near the free end of the carrying lever and a Bowden cable fixed to the actuating rod for said carrying lever.

6. In a lace machine wherein the motions 95 of needles actuated by jacquard card mechanism are transmitted to planet wheel carriers co-acting with planet gear to actuate an embroidery frame, jacquard-operated mechanism for selectively oscillating the 100 planet wheel carriers in one or other direction, comprising two sets of slidable jacks having differently located butts thereon, a jacquard card mechanism operating said jacks selectively, a three-armed lever, an oscillating lever carrying said three-armed 105 lever, feeler bars on two arms of said lever adapted in the oscillation of the carrying lever to co-operate with the butts on said jacks which have not been operated by the jacquard mechanism, an actuating rod for said carrying lever, said actuating rod having an elongated slot therein, a pin on the free end of the carrying lever engaging in the elongated slot, and machine-stopping 110 mechanism operated by a movement of the said pin along the elongated slot.

MAX HADAM.
